ATTORNEYS

UNITED STATES PATENT OFFICE.

MICHAEL FEDORINA, OF CLEVELAND, OHIO.

DESIGN FOR A WICKER OR RUSTIC CHAIR.

42,524.

Specification for Design.

Patented May 14, 1912.

Application filed January 24, 1912. Serial No. 673,259. Term of patent 3½ years.

To all whom it may concern:

Be it known that I, MICHAEL FEDORINA, a subject of the King of Hungary, residing at Cleveland, in the county of Cuyahoga and State of Ohio, have invented a certain new, original, and ornamental Design for a Wicker or Rustic Chair, of which the following is a specification, reference being had to the accompanying drawing, forming a part thereof.

The figure is a perspective view of the wicker or rustic chair, illustrating my new design.

I claim:

The ornamental design for a wicker or rustic chair, as shown.

MICHAEL FEDORINA.

Witnesses:

JOHN BANYKO,
FRANK BENES.
